UNITED STATES PATENT OFFICE.

FRANK S. SAXTON, OF BLISSFIELD, MICHIGAN.

DESIGN FOR AN EASEL STAND.

Application filed July 5, 1928. Serial No. 27,384. Term of patent 7 years.

To all whom it may concern:

Be it known that I, FRANK S. SAXTON, a citizen of the United States, residing at Blissfield, in the county of Lenawee and State of Michigan, have invented a new, original, and ornamental Design for an Easel Stand, of which the following is a specification, reference being had to the accompanying drawing, forming part thereof.

Fig. 1 is a perspective view of the easel stand, showing my new design, and Fig. 2 is a side view of the easel stand.

I claim:

The ornamental design for an easel stand as shown.

In witness whereof I have hereunto signed my name to this specification.

FRANK S. SAXTON.
